UNITED STATES PATENT OFFICE

HOMER D. TRACY, OF RIDGEWOOD, NEW JERSEY, ASSIGNOR TO BARBOUR FLAX SPINNING CO., OF PATERSON, NEW JERSEY, A CORPORATION OF NEW JERSEY

WINDING MACHINE

Application filed February 10, 1928. Serial No. 253,306.

This invention relates to machines for forming conical wound packages. In one type of these machines a conical element for receiving the windings, or rather a paper or equivalent hollow core for the windings, is rotated around an axis passing longitudinally therethrough in parallelism with the taper of the cone (as by said element being a sleeve revoluble around a conical stub over which it is fitted and which is set so that its taper and said axis are parallel), and the yarn guide in receding from the package does so in a path perpendicular to such an axis instead of one perpendicular to the true axis of the cone. The consequence of such a construction is that the ends of the package do not conform to planes (perpendicular to the true axis of the package cone) but the smaller end is dished or concave and the larger or butt end convex, which of course reduces the stability of the wound mass.

My invention contemplates novel means for forming a conical wound package so that the ends thereof may conform to planes perpendicular to the true axis of the package cone, and also so that any desired degree of taper may be attained.

It further contemplates a novel detector generally useful for detecting slubs and the like in yarn or thread.

In the drawings,

Fig. 1 is a side elevation of a complete winding unit embodying the invention, certain parts of the machine frame appearing in section;

Fig. 2 is a front elevation of such unit;

Fig. 3 is a diagrammatic plan of the parts principally concerned in the invention;

Figs. 4 and 5 are plans of the swinging frame and its pivotally adjustable arm;

Figs. 6 and 7 are sections on lines 6—6 and 7—7 of Figs. 4 and 5, respectively;

Figs. 8 and 9 show a detail of the yarn traversing means; and

Fig. 10 shows the slab detector in plan.

In the frame 1 is horizontally journaled a drive-shaft 2 driving, through gearing 3, a horizontal shaft 4 which, through a clutch 5, drives the spindle 6, alined therewith and projecting from the frame, and also, through

a belt-and-pulley system 7, a shaft 8 which, through a pinion thereon (not shown) and meshing with a gear 9, drives a barrel cam 10 whose axis of rotation is horizontal and which causes traverse of the yarn lengthwise of the package being formed. A clutch lever 11 is normally influenced by a spring 12 to hold the clutch 5 open, with the spindle stopped, but is shifted by hand, to start the spindle, until it is dogged by lever 13. This lever is adapted to be automatically tripped by the rise of a push-rod 14 effected, when the yarn breaks, by a lever 15 normally held against falling by the yarn, which it engages at 15^a between the supply package A and a guide at 16. So much is in general well known. The lever 13 is also adapted to be automatically tripped by movement of lever 15 effected from the movable element of a slab-detector, as will hereinafter appear.

B is the quill for the windings, arranged on the spindle.

A movable (here fulcrumed) structure to afford support and a guide for the yarn-traversing means, receiving its motion from cam 10, is provided as follows: 17 is a yoke fulcrumed on the shaft of said cam so that (since said shaft and the spindle axis are parallel) it is movable perpendicularly to the latter; in the present case its movement from the spindle during a winding operation is obtained from the growing package toward which it is normally urged by a weight 17^x, 17^y being a weighted cam-chock engaging its toe 17^z so that it cannot swing inward out of control when, being outward, it is released.

Its horizontal cross-bar 17^b projects forwardly through a slot (Fig. 2) in the front plate of frame 1, forward of which it may have an additional leg 17^c with a bearing on said shaft at 17^d, and it has an arm or extension 18 pivotally adjustable therein so as to be set in parallelism with the taper of the quill, 19 being the pivot and 20 a bolt and nut or equivalent clamping or securing means received by holes 19^a and the hole and slot 20^a (Figs. 4 and 5). The yarn-traversing means includes a yarn-traverser 21 guided in and by the arm 18, a reciprocating traveller 22 guided by cross-bar 17^b of the yoke and 100

reciprocated by the cam 10, and a link 23 pivotally connecting the traverser and traveler. The details of these parts in their preferred form will be later described.

It will appear from the foregoing that when the winding unit is in operation, the tapered core rotating and the yarn-traversing means reciprocating, and the latter moving away from the package being formed as the latter grows in diameter, the ends of the package will be formed in planes perpendicular to the true axis of the package (see Fig. 3). This is because, through those (reciprocating) movements of the traverser by which it places the yarn layers are parallel with the taper of the package, its movement of recession with the support from said axis is perpendicular to the latter. In order to produce packages having different degrees of taper the carried part (as 18) of said support affording the guide for the traverser is adjustable relatively to the carrying part (as 17) of said support and toward or from the package to change the angularity thereof with respect to said axis. In the present example where means, as 10, is present for imparting reciprocation to the traverser which is offset relatively to the package lengthwise of its axis and said parts of the support must be correspondingly offset with respect to each other, a traveller, as 22, is arranged on part 17 of said support for reciprocation by said means and to this the traverser is pivotally connected, as by link 23, to permit the said adjustment thereof.

The traverser is an inverted T-shaped plate having a yarn guide 21^a at the top and its lower edge sliding in a groove 18^a in arm 18, against whose flat face 18^b the plate bears; it may have a bent-off extension 21^b engaged in another groove 18^c to prevent its rising and being unshipped from the arm, and another such extension 21^c affording a pivot for the link 23. The traveller 22 may also be a plate sliding in a slot 17^e of cross-bar 17^b and having, below the latter, a bent-off extension 22^a carrying a roller 22^b which travels in the groove of the cam 10 and, above the plate, opposite extensions 22^c and 22^d respectively engaged in a groove 17^f and affording a pivot for the link.

As for automatic stopping on presence of a slab: A toggle lever 24, controlled by a spring 25, is fulcrumed on a bracket 26 and adapted to be moved by the slab, togglewise, against a stop 26^a thereof and on such movement actuate lever 15 through a link 27. A novel slab detector is mounted on and formed in part by the free end of this lever, thus: 28 and 29 are plates secured to the lever above and below (so that they are thus spaced by) the latter, having yarn-receiving or detecting slots 28^a and 29^a at right angles to each other and entering from edges of the plates and each open laterally of itself to the space be-

tween the plates. This arrangement of the plates, taken with the relative arrangement of the slots, makes it possible for the operator unerringly and quickly to thread the detector—by rotative movement of the yarn first in one and then in the other direction, the yarn entering the space between the plates between the two movements.

Having thus fully described my invention, what I claim is:

1. In combination, the frame, means therein to rotate the tapered wound package being formed, a support movable in the frame from, and in a plane substantially perpendicular to, the true axis of the package, and a yarn traverser arranged to reciprocate in the support, said support having a guideway for the traverser arranged substantially parallel with the taper of the package.

2. In combination, the frame, means therein to rotate the tapered wound packages being formed, a support movable in the frame from, and in a plane substantially perpendicular to, the true axis of the package and including a carrying and a carried part, and a yarn-traverser arranged to reciprocate in said carried part of the support, said carried part having a guideway for the traverser and being adjustable on the carrying part to change the angularity of the guideway with respect to said axis.

3. In combination, the frame, means therein to rotate the tapered wound package being formed, a support movable in the frame from, and in a plane substantially perpendicular to, the true axis of the package and including a carrying and a carried part, and a yarn-traverser arranged to reciprocate in said carried part of the support, said carried part having a guideway for the traverser and being pivotally adjustable in the carrying part around an axis traversing the first axis to change the angularity of the guideway with respect to said axis.

4. In combination, the frame, means therein to rotate the tapered wound package being formed, traverse-imparting means offset relatively to the package lengthwise of its axis of rotation, a support movable in the frame from, and in a plane substantially perpendicular to, the true axis of the package and having a guideway opposite the package and arranged substantially parallel with the taper thereof, and yarn-traversing means reciprocated by the traverse-imparting means and including a yarn-traverser arranged to reciprocate in said guideway.

5. In combination, the frame, means therein to rotate the tapered wound package being formed, traverse-imparting means offset relatively to the package lengthwise of the axis of rotation of the package, a support movable in the frame from, and in a plane substantially perpendicular to, the true axis of the package and having guideways respec-

tively oppose the package and said means, the portion of said support having the second guideway being adjustable relatively to the remainder of said support to change the angularity of such guideway with respect to said true axis, a traveller reciprocated by said means and guided by the first guideway, and a yarn-traverser pivotally connected with and reciprocated by the traveller and guided by the second guideway.

10 6. In combination, the frame, means therein to rotate on its own axis the tapered package being formed, mechanism to control the yarn being wound including a yarn traverser and being movable from, and in a plane substantially perpendicular to, said axis, and means to reciprocate the traverser substantially equal distances whose termini are substantially coincident with planes also perpendicular to said axis.

15 7. In combination, the frame, means therein to rotate on its own axis the tapered package being formed, mechanism to control the yarn being wound including a yarn traverser and being movable from, and in a plane substantially perpendicular to, said axis, and means to reciprocate the traverser substantially equal distances whose termini are substantially coincident with planes also perpendicular to said axis, said mechanism being normally held in wiping contact with the package.

20 8. In combination, the frame, means therein to rotate on its own axis the tapering wound package being formed, a yarn traverser movable in a path extending lengthwise of the package but substantially parallel with the taper thereof, and means to confine the traverser to said path including a support for the traverser movable in the frame from, and in a path substantially perpendicular to, said axis.

25 9. In combination, the frame, means therein to rotate on its own axis the tapering wound package to be formed, a yarn traverser movable in a path extending lengthwise of the package but substantially parallel with the taper thereof, and means to confine the traverser to said path including a support for the traverser movable in the frame from, and in a path substantially perpendicular to, said axis, said support and traverser forming a structure normally held in wiping contact with the package.

30 55 In testimony whereof I affix my signature.
HOMER D. TRACY.
